DESIGN FOR A DISPLAY CONTAINER FOR JEWELRY OR SIMILAR ARTICLE

Milton Weill, New York, N. Y., assignor to Arrow Manufacturing Company, Inc., Hoboken, N. J., a corporation of New Jersey

Application October 19, 1937, Serial No. 72,310

Term of patent 7 years

To all whom it may concern:

Be it known that I, Milton Weill, a citizen of the United States, residing at New York city, in the county and State of New York, have invented a new, original, and ornamental Design for a Display Container for Jewelry or Similar Article, of which the following is a specification, reference being had to the accompanying drawing, forming a part thereof.

Figure 1 is a side elevational view of the display container for jewelry, showing my new design, with the cover in closed position.

Fig. 2 is a front elevational view thereof with the cover in closed position.

Fig. 3 is a side elevational view thereof with the cover in open position.

Fig. 4 is a front elevational view thereof with cover in open position.

I claim:

The ornamental design for a display container for jewelry or similar article, as shown.

MILTON WEILL.
